DESIGN FOR A DRESS

Sara Schwartz, Brooklyn, N. Y.

Application April 6, 1940, Serial No. 91,514

Term of patent 3½ years

To all whom it may concern:

Be it known that I, Sara Schwartz, a citizen of the United States of America and resident of the Borough of Brooklyn, county of Kings, city and State of New York, have invented a new, original, and ornamental Design for a Dress, of which the following is a specification, reference being had to the accompanying drawing forming a part thereof.

In the drawing:

I claim:

The ornamental design for a dress, substantially as shown.

SARA SCHWARTZ.
